Primary Examiner — Brett Miller**CLAIM**

The ornamental design for a rotisserie grill cooker, as shown and described.

DESCRIPTION

FIG. 1 is a front-top-right perspective view of the rotisserie grill cooker showing my new design;

FIG. 2 is a front-plan view thereof;

FIG. 3 is a back-plan view thereof;

FIG. 4 is a left-side view thereof;

FIG. 5 is a right-side view thereof;

FIG. 6 is a top elevation view thereof; and,

FIG. 7 is a bottom elevation view thereof.

The broken lines in FIGS. 1-7 are included for the purpose of showing environmental structure and form no part of the claimed design.
